(57) **CLAIM**

The ornamental design for a syringe, as shown and described herein.

DESCRIPTION

FIG. 1 is a top, front, right side perspective view of a syringe according to the present disclosure.

FIG. 2 is a bottom, front, left side perspective view of the syringe.

FIG. 3 is a front elevation view of the syringe, the rear elevation view being a mirror image.

FIG. 4 is a left side elevation view of the syringe, the right side elevation view being a mirror image.

FIG. 5 is a top plan view of the syringe shown at an enlarged scale.

FIG. 6 is a bottom plan view of the syringe shown at an enlarged scale; and,

FIG. 7 is a top, front, right side exploded perspective view of the syringe.

1 Claim, 4 Drawing Sheets
